WALTER M. AUSTIN, OF SWISSVALE, AND JOSEPH N. MAHONEY, OF WILKINSBURG, PENNSYLVANIA, ASSIGNEES TO WESTINGHOUSE ELECTRIC AND MANUFACTURING COMPANY, A CORPORATION OF PENNSYLVANIA.

CIRCUIT-INTERRUPTING DEVICE.

1,156,655.

Specification of Letters Patent.

Patented Oct. 12, 1915.

Application filed October 14, 1913. Serial No. 795,109.

To all whom it may concern:

Be it known that we, WALTER M. AUSTIN, a citizen of the United States, and a resident of Swissvale, in the county of Allegheny and State of Pennsylvania, and JOSEPH N. MAHONEY, a citizen of the United States, and a resident of Wilkinsburg, in the county of Allegheny and State of Pennsylvania, have invented a new and useful 10 Improvement in Circuit-Interrupting Devices, of which the following is a specification.

Our invention relates to circuit interrupting devices, and particularly to three-pole 15 circuit breakers of the carbon type.

The object of our invention is to provide a multipolar circuit interrupter of the non-closable on overload type having a single operating handle.

20 In a polyphase circuit, the use of a plurality of non-closable-on-overload circuit interrupters without auxiliary knife blade switches has been found to be detrimental, in that any number of interrupters may be 25 closed to cause such translating devices as may be connected to the circuit to be operated on an incorrect number of phases. We provide a multipolar circuit interrupter having a single handle for closing all of the 30 poles simultaneously and also having a simple and inexpensive non-closable-on-overload mechanism that prevents the closing of the same under predetermined conditions.

In the accompanying drawing, Figure 1 35 is a front view of a circuit breaker embodying our invention, shown partially in elevation and partially in section; Fig. 2 is a fragmentary view of the operating mechanism of a circuit interrupter embodying our 40 invention, shown partially in section and partially in elevation; Fig. 3 is a view of a link used in our invention, and Fig. 4 is a view of another link and a latch used in our invention.

45 Our invention comprises a circuit breaker 1, having movable contact members 2, 3 and 4, stationary contact members (not shown), tripping magnets 5 and 6, a cross bar 7 connecting the movable members of the outer 50 contact members 2 and 4, and an operating lever 8. The center contact member 3 comprises a movable arm 9 similar to that of the contact arms of the contact members 2

and 4. The arm 9 is pivotally mounted at a point 10 on stationary projections 11 and 55 is also loosely attached to a shaft 12 carried by the operating lever 8. Lever 8 is also pivotally connected to a link 13 at a point 14. The link 13 is pivotally mounted on one of the projections 11 at a point 15, and has 60 a projection 16 to be engaged by a latch 17 that is integral with a lever 18 which is mounted, as is lever 19, loosely upon the shaft 12. One end of a link 21 is pivotally 65 attached to the lever 19 at a point 20, and its other end is attached to a bell crank latch 22 that is pivotally mounted on the lever 8 to engage a projection 23 on the cross bar 7. The latch 22 is normally held in engagement with the projection 23 by a spring 24 70 attached to the operating lever 8. Each of the tripping magnets 5 and 6 comprises a trip coil 25, a core 26 and a movable armature 27. The armature 27 has a projection 28 on its lower end to engage a common 75 tripping bar 29 which, in turn, has a projection 30 for engaging the levers 18 and 19.

Since the structure of the actual contact members is not new in the art, it will not be described here, except in so far as to state 80 the coöperation between the same and the operating mechanism of our invention.

Assuming the circuit interrupter to be in its closed position, as shown in Fig. 2, if an overload occurs, the armature 27 of one of 85 the tripping magnets 5 and 6 will be attracted, thus causing the tripping bar 29 to engage the levers 18 and 19. Movement of the lever 19 will effect withdrawal of the latch 22 from the cross bar 7, thus releasing 90 the contact-arms of the outer contact members 2 and 4, and movement of the lever 18 will effect withdrawal of the catch 17 from the end 16 of the link 13 and allow the center contact arm 9 to operate. All the contact 95 arms are provided with springs (not shown) which tend to move them from their closed positions, so that, when the cross arm 7 is released from the latch 22, the contact arms are moved quickly to their open positions. 100 On closing the circuit-breaker, the handle 8 is moved upwardly until the latch 22 engages the projection 23 on the cross bar 7. Then the handle 8 is moved downwardly upon the shaft 12 as a pivot, as well as being 105 guided by the link 13, thus latching the

whole mechanism in place when the projection 16 on the link 13 is engaged by the latch 17 on the lever 18.

If an overload occurs when the handle 8 is in the grasp of an attendant, the armature of the tripping magnets operate in the usual way, as hereinbefore described, and cause the tripping bar 29 to move up and the projection 30 to engage the lever 19, thus with 10 drawing the latch 22 and allowing the two contact arms of the contact member 2 and 4 to open. The center arm 9 will remain in its closed position if the handle 8 is held in its closed position. As it is not detrimental to maintain one line of a three-phase circuit closed or harmful to maintain the neutral of a three-wire system closed, our invention provides an effective as well as an inexpensive circuit-breaker with a tripping-free attachment.

Changes in the shape or size of our invention may be made without departing from the scope of same as covered by the appended claims.

25 We claim as our invention:

1. A circuit interrupter comprising a plurality of movable contact members operatively connected together, a movable contact member independent of said contact members, two levers pivotally mounted on said independent contact member, an operating lever, a latch pivotally mounted on said lever and operatively connected to one of said levers, said latch serving to restrain said operatively connected movable contact members, and the other of said levers having means for restraining said independent movable contact member in its closed position, and means for operating said levers to trip 40 said interrupter.

2. A circuit interrupter comprising a plurality of movable contact members, a bar for connecting said plurality of movable contact members together, a movable contact member independent of said contact members, two levers pivotally mounted on said independent contact member, an operating lever, a latch operatively connected to one of said levers, said latch serving to connect said bar and said operating lever together, and the other of said levers having means for restraining said independent movable contact member in its closed position, and means for operating said levers to trip 55 said interrupter.

3. A circuit interrupter comprising three movable contact members, a bar for operatively connecting two of said movable contact members together, an operating mechanism comprising a latch for engaging said bar, two trip coils, two pivotally mounted levers, means actuated by said trip coils for engaging said levers, one of said levers being adapted to latch the movable member 60 that is not connected to the bar in its closed

position, and means for operatively connecting the other lever to the latch that engages the said bar.

4. In a circuit interrupting device, the combination with a plurality of movable contact members, of a bar for connecting all but one of said contact members together, an operating mechanism comprising a trip coil, two levers pivotally mounted on said contact member that is not connected to the bar, an operating lever, a tripping bar actuated by said trip coil and adapted to engage said levers, one of said levers being adapted to restrain the contact member that is not connected to said bar, and a latch operatively connected to the other of said levers for operatively connecting said connecting bar and the said operating lever.

5. A circuit interrupter comprising a plurality of contact arms, a bar for connecting said plurality of contact arms together, a movable contact arm independent of said plurality of contact arms, a tripping device, two pivotally mounted levers, an operating lever, one of said levers being adapted to restrain said independent arm in its closed position, and a latch operatively connected to the other of said levers for latching said operating lever to said connecting bar.

6. A circuit interrupter comprising a plurality of contact arms, a bar for connecting said plurality of contact arms together, a contact arm independent of said contact arms, two pivotally mounted levers, a plurality of trip coils, a tripping bar operated by any of said trip coils and adapted to engage said levers, one of said levers having means for restraining the independent contact arm in its closed position, and a restraining means for said contact arms that are connected together, said restraining means being operatively connected to the other of said levers.

7. A circuit interrupter comprising a plurality of contact arms, a bar for connecting said plurality of contact arms together, a contact arm independent of said contact arms, two pivotally mounted levers, a plurality of trip coils, a tripping bar operated by any of said trip coils and adapted to engage said levers, an operating lever pivotally mounted on said independent contact arm, one of said levers having means for restraining the independent contact arm and the operating lever in their closed positions, and a latch mounted on said operating lever for engaging said connecting bar, said latch being operatively connected to the other of said levers.

8. A circuit interrupter comprising three movable contact arms, means for connecting two of said arms together, and means for latching the other of said arms to the connected arms.

9. A circuit interrupter comprising three

movable contact arms, means for connecting two of said arms together, means for latching the other of said arms to the connected arms, and means for restraining the arm that is latched to said connected arms in its closed position.

10. A circuit interrupter comprising three movable contact arms, means for connecting two of said arms together, means for latching the other of said arms to the connected arms, means for restraining the arm that is latched to said connected arms in its closed position, and means for tripping said connected arms under predetermined conditions.

11. A circuit interrupter comprising a

contact arm, a second contact arm independent of the first mentioned contact arm, means for latching said second arm to said independent arm, means for restraining said independent arm in its closed position, and means for tripping the said first mentioned arm under predetermined conditions.

In testimony whereof, we have hereunto subscribed our names this 30th day of Sept. 25 1913.

WALTER M. AUSTIN.
JOSEPH N. MAHONEY.
